DESIGN FOR A TRAY FOR DISPLAYING ARTICLES OF MERCHANDISE

George C. Holt, Fort Madison, Iowa, assignor to
W. A. Sheaffer Pen Company, Fort Madison,
Iowa, a corporation of Delaware

Application September 10, 1938, Serial No. 79,827

Term of patent 3½ years

To all whom it may concern:

Be it known that I, George C. Holt, a citizen of the United States, residing at Fort Madison, in the county of Lee and State of Iowa, have invented a new, original, and ornamental Design for a Tray for Displaying Articles of Merchandise, of which the following is a specification, reference being had to the accompanying drawing, forming a part thereof.

The figure is a perspective view of the tray for displaying articles of merchandise showing my design.

I claim:

The ornamental design for a tray for displaying articles of merchandise, substantially as shown.

GEORGE C. HOLT.
